UNITED STATES PATENT OFFICE.

EDGAR B. SYMONS, OF LOS ANGELES, CALIFORNIA, ASSIGNOR TO SYMONS BROTHERS COMPANY, OF MILWAUKEE, WISCONSIN, A CORPORATION OF SOUTH DAKOTA.

CRUSHING HEAD.

Application filed November 14, 1924. Serial No. 749,813.

To all whom it may concern:

Be it known that I, EDGAR B. SYMONS, a citizen of the United States, residing at Los Angeles, in the county of Los Angeles and 5 State of California, have invented a certain new and useful Improvement in Crushing Heads, of which the following is a specification.

My invention relates to improvements in 10 gyratory cone crushing machines of the type in which the material to be crushed is fed, or is allowed to flow by gravity, through a crushing zone between a fixed concave and a cone gyrating within the concave.

15 One object of my invention is to provide a new and improved type of gyratory crusher adapted for fine crushing. Another object is to provide such a crusher wherein means are provided to permit a very fine 20 adjustment of the opposed cone and concave. Another object is to provide a yieldingly supported crushing element, and particularly, a yieldingly supported crushing cone. Another object is to provide a gyratory 25 crusher for fine reduction, which can be set for small sizes of output without risk of stoppage or breakage upon the passage through the fine crushing zone of relatively large masses of uncrushable material. Another 30 object is to provide a simple and efficient oiling system, to prevent the entry of dust, water or other foreign materials into the bearings, and to prevent oil leakage. Another object is to provide adjusting 35 means for the concave supporting spider. Another object is to provide an improved type of sectional crushing mantle. Other objects will appear from time to time in the course of the specification and claims.

40 My invention is illustrated more or less diagrammatically in the accompanying drawings, wherein:

Figure 1 is a plan view;

45 Figure 2 is a section along the line 2—2 of Figure 1;

Figure 3 is a section on the line 3—3 of Figure 1;

Figure 4 is an enlarged view of one of the valves shown in Figure 3;

50 Figure 5 is a side elevation of the cone with the concave in section;

Figure 6 is a section on the line 6—6 of Fig. 2;

Figure 7 is a detailed view of an adjusting shaft;

55 Figure 8 is a section on the line 8—8 of Figure 2.

Like parts are indicated by like characters throughout the specification and drawings.

60 A is a bed upon which rests a frame A¹ outwardly flanged as at A² for stiffness, and provided at its top with the reinforcing flange A³. A⁴ A⁴ are radial arms extending inwardly from the flange A² to support a rigid bearing sleeve A⁵. Upon one side of this sleeve is a gear case A⁶, from which projects laterally a horizontal sleeve A⁷. The upper end of the sleeve A⁵ is provided with a gear case A¹⁰, which is formed by a 65 flange A⁸ projecting outwardly from the body of the sleeve A⁵ and closed by the bearing cap A⁹. The sleeve A⁵ is provided with a tightly fitted lining A¹¹, outwardly flanged at its upper end.

75 B is an outwardly cylindrical, eccentrically apertured sleeve mounted for rotation within the outer babbitt bearing A¹² within the lining A¹¹ of the sleeve A⁵. It is flanged as at B² and has an annular ball bearing B¹ resting upon the flanged upper end of the lining A¹¹ to support the downward thrust caused by the weight of the eccentric and its associated parts. B³ is a ring gear secured to the under side of the flange B² 80 and located within the gear case A¹⁰. B⁴ is a beveled pinion in mesh with the gear B³ and mounted on the drive shaft B⁵, which rotates in any suitable bearings B⁶, carried by the bearing support B⁷, which in turn 85 is carried in the sleeve A⁷. B¹⁰ is a belt pulley keyed to the shaft B⁵.

90 The bearing cap A⁹ is spherically formed upon its upper side as at C and supports a babbitt facing C¹, which provides a non-frictional supporting surface for the opposed spherical bearing surface C² of the head C³. The head C³ is centrally apertured, and seats upon the upper tapered surface C⁵ of the gyratory shaft C⁶, the lower 95 section C⁷ of which penetrates within the eccentric aperture of the sleeve B and is mounted within an inner babbitt bearing C⁸. The head is provided with a skirt C¹⁰ bolted or otherwise removably secured to the 100 ledge C¹¹ about the head and terminating

in a spherically surfaced flange C^{12} adapted to engage the oil packing ring C^{13} in a spherical bearing surface C^{14} which is concentric with the main spherical bearing.

5 The upper end of the head is surrounded by a ledge D which is arcuate in cross-section as at D^1 , the arcuate portion forming a bearing or tilting support for the open bottomed, hollow crushing cone D^2 , which 10 is inwardly flanged at the top, as at D^3 , about its central aperture, to conform generally to the shape of the ledge. The periphery of the cone is reinforced, for example, by a cylindrical section D^4 , although 15 other reinforcing might be used.

Mounted upon the hollow cone is a mantle comprising a plurality of conical rings E , E^1 , which may be of manganese steel or other suitable material, and which are provided about their periphery with opposed angular portions E^2 adapted to conform to and penetrate into angular recesses E^3 in the adjacent rings. E^4 is a securing or pressure transmitting ring adapted to engage 20 the uppermost manganese ring and to conform to its angular irregularities. The manganese rings may rest directly upon the mantle but are preferably supported upon a layer of zinc or other suitable material E^5 .

25 I provide unitary means for holding the head upon the shaft, the cone upon the head, and the mantle upon the cone. The lock nut G is screw threaded upon the upper portion G^1 of the shaft C^6 and may be 30 locked in position, for example by the key G^2 . Between it and the mantle cone and head are compressed a plurality of sets of powerful springs, comprising an outer spiral spring G^3 and an inner spiral spring 35 G^4 , the outer and inner springs being of opposite pitch. These sets of springs are compressed between the opposed spring seats G^5 , G^6 . The spring seat G^5 is seated by the pressure of the spring against the lock nut G and 40 is provided with a downwardly projecting sleeve G^7 , in which are a plurality of apertures G^8 . Upwardly projecting from the lower spring seat G^6 is a central sleeve G^{10} 45 the upper end of which is provided with teeth or lugs which mesh with the apertures G^8 and prevent relative rotation of the two spring seats. The bottom of the spring seat G^6 is provided with a spherical bearing surface G^{11} opposed to and conforming to 50 the spherical surface G^{12} of the ring G^{13} , the bottom of said ring G^{13} being in engagement with the top of the ring E^4 . Projecting upwardly and slightly outwardly from the ring G^{13} , and surrounding the springs, is 55 the cylindrical or slightly conical casing H , which supports the feed plate H^1 , the upper surface of which forms a very flat cone. The plate H^1 is positioned above and out of 60 contact with the nut G and the top of the shaft C^6 . It will be understood that the

cone, mantle and feed plate can move only as a unit, owing to the pressure of the springs G , G^1 .

65 J is a conical spider having a cylindrical flange J^1 adapted to penetrate and be vertically adjustable in the frame A^1 . It is provided with reinforcing ribs J^2 and three laterally extended lugs J^3 . Adjusting bolts J^4 pass through the bosses J^5 on the ring or frame A^1 , the fit being relatively loose. The lower portion of the adjusting bolt J^4 is screw-threaded as at J^{10} and is engaged by a split nut J^6 , the two parts of which are connected by the cap screw J^8 which passes therethrough and through the flange or boss J^9 upon the frame A^1 . The upper portion of the adjusting bolt J^4 is screw-threaded as at J^{10} and passes through the lugs J^3 with a relatively loose fit. The lugs J^3 are countersunk as at J^{15} and the upper and lower supporting nuts J^{16} , J^{17} have conical surfaces to engage these countersinks, so that when the upper adjusting nuts have been slackened off the lower nuts may be rotated to raise or lower the spider and to 75 adjust it toward or from the crushing cone.

80 K , K^1 are concave mantle sections carried by the spider and provided with zinc or other suitable packing K^2 . K^3 is an upper cylindrical portion about the top of the section K , the top of which is downwardly tapered as at K^4 to conform to the downward taper of the upper edge of the spider. K^5 are lugs about the lower periphery of 85 the section K^1 and are engaged by the locking bolts K^6 which pass through the spider and serve to lock the concave sections in 90 position.

95 L is any suitable cylindrical inlet member aligned above the feed plate and adapted to 100 deliver material thereto. It is positioned in the central aperture of the cover or hopper plate L^1 , which may support any suitable quantity of the material to be crushed, thus 105 building up a head or reservoir of material. The plate L^1 is supported in the ring L^2 , which in turn is supported by the arms L^3 upon the reduced, screw-threaded portions L^4 of the adjusting bolt J^4 , being adjusted 110 therewith by the adjusting bolts L^5 , L^6 .

115 M is a pump supporting pedestal positioned beyond the pulley B^{10} and supporting the outwardly extending end B^{12} of the drive shaft B^5 . Secured in any suitable manner in the end of said drive shaft is a worm M^1 in mesh with a worm gear M^2 positioned in any suitable housing M^3 having, for example, the removable cover M^4 . Upon each side of the worm gear M^2 is an eccentric stud M^5 , about which is fitted the circular end M^6 of the link M^7 , the opposite end of which is pivoted to the guiding slide M^8 of a piston M^9 . M^{10} is a line passing 120 through the cylinder M^{11} of said piston and being provided both at its inlet and at its 125 outlet.

130

outlet from said cylinder with a valve comprising, for example, a hinged flap M^{12} and adapted to permit the passage of fluid in said pipe in but one direction. M^{14} is a smaller piston downwardly projecting from the end of the piston M^9 and penetrating the smaller cylinder M^{15} , through which passes the line M^{16} provided with similar valves M^{17} . The oil line M^{16} extends to a cap O , which closes the bottom of the sleeve A^6 . The oil pumped therethrough passes upwardly along the inner and outer babbitts by means of the axial slots or apertures O^1 , O^2 in said babbitts. The oil thence passes through the ball bearing B^1 and into the interior of the casing A^{16} or over the top of the flange B^2 , and thence into said casing. The oil passes thence by means of the return line O^5 to any suitable filter and thus to the main oil supply, to be drawn thence again for use in constant circulation. The bevel gear B^3 , in the course of its rotation, centrifugally throws oil into the oil pocket O^6 , whence it passes by the inclined oil passage O^7 to lubricate the drive shaft bearings B^6 . The oil line M^{16} passes directly to a circumferential oiling aperture P , positioned about the spherical bearing surface of the cap A^9 . As the head is gyrated some of the oil works outwardly over the rim of the bearing surface and into the circumferential oil well P^1 , whence it flows by the inclined passage P^2 to the gear casing A^{16} . The oil which works inwardly toward the shaft passes downwardly along the shaft and over the flange B^2 into the oil casing A^{16} .

Since extremely powerful springs are required to exert the requisite pressure upon mantle, cone and head, I provide means for permitting the assembly of the spring seats at the factory and their shipment as an assembled unit. Thus when replacement is necessary the spring unit may be shipped and installed without special equipment at the plant or location where the crusher is being used. Within a plurality of the outer spiral springs G^3 the inner spiral spring G^4 is omitted, its place being taken, when the spring unit is being prepared for shipment, by the bolt G^{20} , which passes through the aperture G^{21} in the upper spring seat G^5 and is screw threaded into the lower spring seat as at G^{22} . These bolts or screws hold the two seats G^5 G^6 against axial movement in relation to each other in response to the compression of the springs, and of course the meshing of the upwardly projecting sleeve G^{10} with the downwardly projecting sleeve G^7 prevents their relative rotation and the twisting of the springs. The unit so assembled is dropped over the end of the shaft and the lock nut G^2 is screwed down until it contacts the upper spring seat, when it is held against further rotation by the insertion of the key. The bolt G^{20} can then

be removed and the springs will at once expand and exert a downward pressure against the mantle, cone and head.

The use and operation of my invention are as follows:

When the machine is set up as shown in the drawings, the drive shaft is rotated and causes the eccentric sleeve to rotate in its bearing. As the eccentric rotates it gyrates the eccentric shaft and, through the shaft, gyrates the cone supporting head about its large spherical bearing. Upon the head is mounted the open bottomed crushing cone, the lower periphery of which is reinforced, for example, by a cylindrical section. The upper edge of the cone is inwardly turned and is provided with a rolling bearing surface conforming to the shoulder about the top of the head.

Upon the cone is placed the actual crushing element, a mantle, preferably of manganese steel. I provide unit means for holding the head firmly in position upon the shaft and for holding the cone upon the head, and the head upon the mantle. These means consist of an upper spring seat and a lower spring seat with a plurality of very powerful springs compressed therebetween. By the compression of these springs the upper spring seat is forced upwardly against the massive lock nut at the top of the shaft. The lower spring seat is thrust down toward the mantle cone assembly and holds it relatively firmly against the head.

Since I use my crusher for fine reduction and wish to set the cone very close to the mantle, I provide a yielding release which will permit the passage through the crushing zone of uncrushable material when, by any chance, it passes therethrough, without either stopping the machine or causing breakage. I obtain this result by providing the lower spring seat with a spherical bearing surface which engages an opposed spherical bearing surface upon a compression ring which in turn delivers the force of the springs downwardly against the upper edge of the mantle. The mantle is by this pressure firmly seated upon the cone and as the manganese tends to spread or stretch in the course of the crushing action, it is nevertheless held firmly against the cone, since, as it stretches, it is simply pressed farther down on the cone by the spring pressure. The mantle also serves as a transmitter of this pressure to the cone itself, which is thereby firmly seated upon the head in the position shown in Figure 2. However, if an unbreakable piece of material passes between the cone and the opposed concave, the strength of the springs is such that they will be compressed before any breakage or stoppage of the machine can take place. The cone simply tilts or rocks on the head, the ledge about the top of the head serving

as the fulcrum, and the cone forming, in a sense, a bell crank lever. As the cone is tilted, the spherical bearing surface of the ring is lifted, particularly on the side of the cone opposite to the interfering material. However, the lower spring seat, being spherically surfaced, does not substantially change its position and the result is merely an upward lifting of the seat and a compression of the springs. Since the spring chamber is normally kept filled with hard oil, the opposed spherical surfaces are properly lubricated and the compression caused by the interposition of the uncrushable material is substantially equally absorbed by all the springs, and the pressure of the springs is constantly and uniformly distributed about the entire periphery of the mantle and cone. With this spring release a very fine adjustment of the cone and concave may be made without risk of stoppage or breakage of the cone. If a piece of iron, for example, passes through the crushing zone the cone instead of cracking, will tilt. If the material being crushed is damp and compresses into an uncrushable mass the machine will not tend to stop and the only unfavorable result will be that it will permit a little over-size and a few flakes of the compressed material to pass therethrough.

The material to be crushed is fed in from above, falling freely under gravity into the crushing space between the concave and the cone. As the cone gyrates material will be wedged or pinched between it and the concave and each particle as soon as it has been crushed will commence to fall freely away from the concave, the distance of its fall depending on the relation between the acceleration due to gravity, the rate and length of gyration of the cone and the size of the particle. The particles will fall vertically until they strike the cone and will then be deflected outwardly and downwardly until the particles reach a point at which the distance between the cone and the concave, at the instant the particle arrives, is equal to the diameter of the particle. At this point the downward movement of the particle ceases until it has been crushed, and the process is repeated.

Toward its bottom the concave approaches parallelism with the cone, it being so shaped for the purpose of insuring that all material discharged from the crusher receives the maximum crushing action, or, in other words, that all material discharged through the crusher shall at some time be crushed between the opposed concave and cone when the concave and cone are at their closest to each other. The length of the zone of parallelism is governed by two factors; the speed imparted to the material by gravity, gravity being a constant force, and the interval of time between the crushing impacts

when the material is permitted to drop as it is released by the increasing distance between the opposed cone and concave. The interval of time is governed absolutely by the speed of operation of the machine. The length of the zone of parallelism must be such that all the material passing through the zone will stay in that zone long enough to be caught at least once between the cone and the concave where they make their closest approach to each other, the maximum distance between concave and cone being far greater than the ultimate size of the material crushed. As the material drops freely through the crushing zone between crushing impacts, the relation of the length of the parallel zone to the interval between crushing impacts must be such that no particle can drop all the way through the zone before it is caught and crushed between the cone and concave at their line of closest approach.

Vertical adjustment of the concave is provided by means of three adjusting screws. In order to manipulate them it is necessary first to release the clamp screw which locks the concave in the split portion of the frame, and when this has been done and without further dismantling of the machine, the lower supporting nuts can be backed off until proper adjustment has been made, when the upper lock nuts can be screwed down to take the crushing pressure. Then the clamp nut and bolt is tightened up. The holding nuts are beveled and the bolt is of course somewhat smaller than the aperture through which it passes in the lug of the spider. Therefore as the adjusting nuts of one adjusting bolt are moved up or down the two remaining bolts and their associated nuts serve as a hinge about which the concave swings.

In the initial factory adjustment of the crusher the individual adjusting bolts or shafts are initially set or adjusted. The adjusting shafts pass through lugs on the frame with a relatively large clearance. In adjusting the spider the first step is to screw the adjusting shaft through the split nut until the bottom of the shaft projects through the nut, as shown in Figure 2, and then the lower spider engaging nut may be lowered into position against the top of the frame. The cap screw is then tightened to lock the split nut about the lower threaded end of the adjusting shaft to prevent further rotation of the shaft and to hold it in permanent position. The split clamp nut has V-shaped threads and when it is tightly clamped an enormous pressure is brought to bear on the shaft, amply sufficient to prevent it from turning. Its engagement with the split nut of course prevents vertical movement of the shaft since the nut is positively locked to the frame by the cap screw.

When the adjusting shaft has thus been permanently set in place, then the lower spider adjusting nut is moved to the proper position and the spider is dropped into place, resting on the lower adjusting nuts of the various adjusting shafts. Then the upper spider engaging nuts are positioned and the crusher is ready for use.

The split nut at the bottom of the shaft has as its function not merely to hold the adjusting shaft against vertical movement, but to make it possible to remove the lower part of the shaft in case of breakage. If the shaft breaks at all it is likely to break adjacent its upper point of entry into the frame. Under such circumstances its removal is extremely difficult unless access is had to its lower end. When such breakage takes place it is only necessary to loosen the split nut and the shaft may be forced through out of the frame.

Another function is to hold the shaft against rotation in case the upper adjusting nut is held against easy removal by the filling of the threads with dust or by their becoming deformed. When the lower split clamp nut is clamped about the lower end of the adjusting shaft rotation is impossible and the upper spider engaging nut can be more readily removed.

The material to be crushed may if desired be permitted to accumulate in any suitable species of hopper or container about the perforated cover plate. Material then flows through the central aperture of the cover plate and forms a column resting on the feed plate. This column of course is of general conic form and material from its base is continuously fed outwardly by the rotation and gyration of said plate. The cover plate may be vertically adjusted to regulate the flow of material to the feed plate and when so adjusted, the feed plate will feed a substantially constant volume of material to the crushing zone, the material being delivered substantially uniformly, about the annular entrance into the crushing zone.

The feed plate forms the top of the casing or housing which protects the springs, and is supported by the relatively cylindrical housing element which protects and incloses the springs, and which is in turn secured to the annular upper extension of the mantle, as shown in Figure 2.

The oiling system is simple and entirely concealed and is internal, the oil being supplied to every bearing from the single oil reservoir with the sole exception that the interior of the spring housing may be filled partly or substantially entirely with hard oil. The double piston pump pumps oil simultaneously through the two lines, one of these oil lines leading to a substantially lenticular chamber beneath the eccentric. Vertical oil ducts are cut or formed in the

babbitts between shaft and eccentric and between the eccentric and its outer bearing sleeve. These are positioned on the side of minimum pressure. Oil is pumped up these oil ducts, the oil from the outer of said ducts passing through the ball bearings which support the outwardly projecting flange of the eccentric and the oil from the inner being discharged over the top of said flange, the oil from both flowing back into the main gear housing about the eccentric. The other oil line leads, as shown in Figure 2, to the spherical bearing of the head, and passes thereabout by a circumferential duct, some of it escaping thence inwardly to the central aperture and supporting cap and passing thence outwardly over the eccentric flange, and the rest passing outwardly into the circumferential oil sump. Since the eccentric is constantly rotating, the vertical oil ducts in the babbitts are constantly oiling the bearing surfaces of shaft, eccentric and outer bearing sleeve. As the head is constantly oscillating, the oil which is delivered to the circumferential channel is constantly being spread across the opposed bearing surfaces. The oil ducts as they pass through the pump are provided with any suitable check valves to prevent any back feed or escape of the oil. Thus the level of the oil in the oiling system does not decline upon stoppage of the crusher and pump. The oil ducts along the eccentric are also full of oil since the oil can escape only from the level of the ball bearings. The oil in the line to the spherical bearings is always at the level or substantially up to the level of its inlet into the circumferential oil passage. Thus the entire machine is properly lubricated within a stroke or two after the crusher has started up, and the chance of any of the bearings burning out is negligible.

The actual crushing, the contact with the material being crushed, falls upon the opposed mantles of cone and concave, and in practice the wear is heavier about the lower edges than anywhere else. For this reason, instead of using one piece mantles, I provide mantles made of two or more rings or conic sections, so that as the lower section wears down it may be replaced by a new section, the upper section being replaced at much greater intervals. I employ a mantle for the concave in which the lower or outer section also serves as a locking means for holding the upper sections in position, it being provided with perforated lugs around its outer edge, through which pass the bolts which secure it in position against the inside of the spider.

The mantle upon the cone is also made in separate sections and since the mantle is not positively secured upon the cone, being positioned thereupon by the pressure of the

springs, I provide against relative rotation and loosening of the parts upon the cone by opposed inclined ratchet surfaces upon the adjacent edges of the various sections. I illustrate these as opposed angular plane surfaced projections upon one element, and correspondingly shaped apertures upon the other. Relative rotation of the adjacent mantle elements naturally serves to force the lower mantle downwardly upon the cone. The relative rotation is not merely largely reduced and practically eliminated, but it is actually employed to seat the mantle element more firmly upon the cone. In practice I prefer to use conic ring sections, each of which has spaced above its periphery four of the angular projections or corresponding apertures, but any suitable number might be used from one up. When it is desired to remove or replace the mantle or any portion thereof, the fastening bolts are inserted in the spring unit and the opposed springs are secured thereby against relative axial movement. Then the main shaft lock nut is removed, the springs are moved as a unit and the mantle sections are then lifted off.

Whereas I have shown a thoroughly practical and operative device, it will be realized that many changes might be made in the size, shape, number, disposition and relation of parts without departing from the spirit of my invention, and I therefore wish the description and drawings to be taken as in a broad sense illustrative, rather than as limiting me to the specific form or forms described and shown.

I claim:

1. In a gyratory crusher, a crushing concave, a head mounted within said concave and means for gyrating it, a crushing cone mounted upon said head, and yielding means for holding said cone in position thereupon, and against movement in relation thereto.
2. In a gyratory crusher, a concave, a head mounted therewithin, and means for gyrating it thereabout, and a crushing cone tiltably mounted upon said head.
3. In a gyratory crusher, a concave, a head mounted therewithin, and means for gyrating it thereabout, a crushing cone tiltably mounted upon said head, and yielding means for normally holding said cone against tilting movement in relation to said head.
4. In a gyratory crusher, a concave, a head mounted therewithin, and means for gyrating it thereabout, a truncated crushing cone tiltably mounted upon said head, the cone engaging the head only about the top of the cone, and yielding means, operative against the upper edge of the cone, for normally holding said cone against tilting movement in relation to said head.
5. In a gyratory crusher, a concave, a head mounted therewithin, and means for gyrat-

ing it, comprising in part a central shaft, adjacent the upper end of which the head is mounted, a crushing cone tiltably mounted upon said head and engaging it only about the top of the cone, and means for normally holding said cone against movement in relation to said head comprising a plurality of springs interposed and compressed between the top of said cone and said central shaft.

6. In a gyratory crusher, a crushing concave, a head mounted within said concave, and means for gyrating it, a crushing cone mounted upon said head and yieldingly held thereupon.

7. In a gyratory crusher, a crushing concave, a head mounted within said concave, and means for gyrating it, a crushing cone mounted upon said head, a mantle mounted upon said cone and yielding means for holding said mantle and cone upon said head.

8. In a gyratory crusher, a crushing concave, a head mounted within said concave, and means for gyrating it, a crushing cone mounted upon said head, a mantle mounted upon said cone, and yielding means for holding said mantle upon said cone.

9. In a gyratory crusher, a crushing concave, a head mounted within said concave, and means for gyrating it, a crushing cone mounted on said head, a mantle mounted upon said cone, and yielding means for holding said mantle on said cone and said cone on said head.

10. In a gyratory crusher, a crushing concave, a head mounted within said concave, and means for gyrating it, a crushing cone mounted upon said head, said cone and head being provided with opposed substantially arcuate bearing surfaces, and yielding means for normally holding said cone against relative movement in relation to said head.

11. In a gyratory crusher, a crushing concave, a vertical shaft mounted within said concave, and means for gyrating it, a crushing cone tiltably mounted upon said shaft, and yielding means for holding said cone normally against tilting in relation to said shaft.

12. In a gyratory crusher, a crushing concave, a vertical shaft mounted within said concave, and means for gyrating it, a crushing cone tiltably mounted upon said shaft, and yielding means for holding said cone normally against movement in relation to said shaft, said yielding means being adapted to permit the cone to tilt in relation to the shaft in response to a predetermined pressure against the side of the cone.

13. In a gyratory crusher, a crushing concave, a vertical shaft mounted within said concave, means for gyrating it, a crushing cone tiltably mounted upon said shaft, said cone and shaft being provided with opposed arcuate bearing surfaces adjacent the top of the cone, and yielding means for holding

said cone normally against movement in relation to said shaft.

14. In a gyratory crusher, a crushing concave, a vertical shaft positioned within said concave, means for gyrating it, a crushing cone positioned adjacent the top of said shaft, a member engaging the top of said cone, a member mounted upon said shaft, and a plurality of spiral springs compressed between said members.

15. In a gyratory crusher, a crushing concave, a central shaft and means for gyrating it therewithin, a head adjacent the top of said shaft, a crushing cone tiltably mounted upon said head, a member positioned above said cone and adapted to transmit pressure thereto, a member held against axial movement in relation to said shaft and positioned above said cone and said first member, and yielding means compressed between said members and adapted to thrust the lower of said members downwardly toward said cone.

16. In a gyratory crusher, a concave, a gyratory shaft positioned within said concave, and means for gyrating it, a head mounted upon said shaft, a cone mounted upon said head, a crushing mantle mounted upon said cone and unitary means for securing said mantle upon said cone, said cone upon said head, and said head upon said shaft.

17. In a gyratory crusher, a concave, a gyratory shaft positioned therewithin, and means for gyrating it, a head mounted upon said shaft, a cone mounted upon said head, a crushing mantle mounted upon said cone, and unitary means for securing said mantle upon said cone, said cone upon said head and said head upon said shaft, comprising a member adapted to transmit pressure to said mantle, a member positioned thereabove and fixed against axial movement in relation to said shaft, and yielding means compressed therebetween.

45. 18. In a gyratory crusher, a concave, a gyratory shaft positioned therewithin, and means for gyrating it, a head mounted upon said shaft, a cone mounted upon said head, a crushing mantle mounted upon said cone, and unitary means for securing said mantle upon said cone, said cone upon said head and said head upon said shaft, comprising a member adapted to transmit pressure to said mantle, a member positioned thereabove and fixed against axial movement in relation to said shaft, and a plurality of spiral springs compressed therebetween.

60. 19. In a gyratory crusher, a concave, a gyratory shaft positioned therewithin, and means for gyrating it, a head mounted upon said shaft, a cone mounted upon said head, a crushing mantle mounted upon said cone, and unitary means for securing said mantle upon said cone, said cone upon said head

and said head upon said shaft, comprising a member adapted to transmit pressure to the upper edge of said mantle, a spherical bearing surface thereupon, a member thereabove having an opposed spherical bearing surface 70 adapted to conform to said first mentioned bearing surface, and axially movable along the shaft, a member positioned thereabove and fixed against axial movement in relation to said shaft, and yielding means compressed 75 between said two members.

20. In a gyratory crusher, a concave, a gyratory shaft positioned therewithin and means for gyrating it, a head mounted upon said shaft, a cone mounted upon said head 80 and yielding means for holding said cone upon said head, comprising a member adapted to transmit pressure to said cone, a member positioned thereabove, and fixed against axial movement in relation to said 85 shaft, a plurality of spiral springs compressed therebetween, and means for preventing relative rotation of said member.

21. In a gyratory crusher, a concave, a gyratory shaft positioned therewithin and 90 means for gyrating it, a crushing cone tiltably mounted upon said shaft and yielding means for holding said cone normally against movement in relation to said shaft, comprising a member adapted to transmit 95 pressure to said cone, and having a spherical bearing surface thereabout, a member positioned thereabove, and having a spherical bearing surface about its lower portion adapted to conform to said first mentioned bearing surface, a member positioned thereabove, and fixed against axial movement in relation to said shaft, and yielding means compressed between said last two members.

22. In a gyratory crusher, a crushing concave, a head mounted within said concave and means for gyrating it, a crushing cone tiltably mounted upon said head and means for exerting a substantially uniform downward pressure about the upper edge of said cone, when said cone is tilted.

23. In a gyratory crusher, a crushing concave, a head mounted within said concave, and means for gyrating it, a crushing cone and means for holding it in position upon said head comprising a plurality of spiral springs interposed between the top of said cone and said shaft, and means for equalizing the pressure of said springs when said cone is tilted.

24. In a gyratory crusher, a crushing concave, a shaft mounted within said concave and means for gyrating it, a crushing cone tiltably mounted upon said shaft and means for exerting a substantially uniform downward pressure about the upper edge of said cone when said cone is tilted.

25. In a gyratory crusher, a crushing concave, a shaft mounted within said concave, a crushing cone mounted upon said shaft,

thereabout, an oil pumping means, and separate oiling passages extending from said pumping means to the cone supporting bearing and the shaft bearing, and automatic means for maintaining said passages constantly filled with oil.

38. In a gyratory crusher, a crushing concave and a crushing cone positioned therewithin, a support for the said cone provided with a bearing surface adapted to engage an opposed bearing surface on said cone, a shaft adapted to gyrate said cone, and a bearing thereabout, an oil pumping means, and separate oiling passage extending from said pumping means to the cone supporting bearing and to the bottom of the shaft bearing, oil ducts extending upwardly along said shaft bearing and automatic means for maintaining said passages and ducts constantly filled with oil.

39. In a gyratory crusher, a crushing concave, a crushing cone positioned therewithin and means for gyrating it, a supporting member for said cone, the cone being tiltably mounted in relation to said supporting member, securing means adapted to hold the cone normally in rigid relation with said supporting member, and adapted to permit said cone to tilt in relation thereto, in response to a predetermined pressure against the side of the cone.

40. In a gyratory crusher, a crushing concave, a crushing cone positioned therewithin and means for gyrating it, a supporting member for said cone, the cone being tiltably mounted in relation to said supporting member, securing means adapted to hold the cone normally in rigid relation with said supporting member, and adapted to permit said cone to tilt in relation thereto in response to a predetermined pressure against the side of the cone, comprising a yielding member positioned above said cone and adapted to exert a downward pressure against the top thereof.

41. In a gyratory crusher, a crushing concave, a truncated crushing cone positioned therewithin and means for gyrating it, a supporting member for said cone, the cone being tiltably mounted in relation to said

supporting member, securing means adapted to hold the cone normally in rigid relation with said supporting member, and adapted to permit said cone to tilt in relation thereto in response to a predetermined pressure 55 against the side of the cone, comprising a yielding member positioned above said cone and adapted to exert a downward pressure against the upper edge thereof.

42. In a gyratory crusher, a pair of opposed crushing elements, the mean distance between which decreases from top to bottom of the crushing zone, comprising a crushing concave, a cone mounted therewithin, means for gyrating it, and yielding 65 securing means for one of said crushing elements adapted to permit it to tilt laterally away from the other in response to a predetermined pressure thereagainst.

43. In a gyratory crusher, a pair of opposed crushing elements, the mean distance between which decreases from top to bottom of the crushing zone, comprising a crushing concave, a cone mounted therewithin, means for gyrating it, and yielding securing means 75 for one of said crushing elements adapted to permit it to tilt laterally away from the other in response to a predetermined pressure thereagainst, the fulcrum point for said tilting action being positioned adjacent the 80 top of the tilting element.

44. In a gyratory crusher, a pair of opposed crushing elements, comprising a crushing concave, a cone mounted therewithin, a fixed supporting member for said concave, a supporting member for said cone and means for gyrating it, the opposed cone and concave both being normally fixed against movement in relation to their respective supporting members, a yielding supporting means interposed between one of said crushing elements and its supporting member, adapted to permit it to move laterally away from the other in response to a predetermined pressure thereagainst in excess of normal crushing pressure. 95

Signed at Los Angeles, county of Los Angeles and State of California, this 5th day of November, 1924.

EDGAR B. SYMONS.
